PARACHUTE OPENING MEANS

Giuseppe Tomasetta, Bronx, N. Y.

Application July 30, 1938, Serial No. 222,157

3 Claims. (Cl. 244—149)

This invention relates to aerial apparatus adapted to expand when exposed to the resistance of the air, and when so expanded as to support a considerable weight, permitting it to slowly and safely descend to the earth.

An object of the invention is to provide a parachute structure having, when it is desired to operate it, an unobstructed space at its lower edges, whereby it is immediately and positively opened to its full extent automatically upon passing through the air, as by having a weight attached at a high or low altitude and released from whatever may have previously supported it.

A further feature is in the provision of a parachute that may be closely and compactly folded, thereby requiring a minimum of space in an aircraft where such apparatus are required as safety appliances in the event of accident or mishap occurring.

These highly important objects are accomplished by the novel construction and arrangement of simple parts hereinafter described and shown in the annexed drawing, forming an essential component of this disclosure, and in which:

Figure 1 is a side view of an embodiment of the invention, shown in its closed condition, as for storage.

Figure 2 is a similar view of the same, shown in an expanded, operative position.

Figure 3 is a plan view of the parachute frame, parts being shown in section and the superstructure omitted.

Figure 4 is a sectional view looking on line 4—4 of Figure 3.

Figure 5 is an enlarged longitudinal sectional view of one of the guy rod ends.

Referring in greater detail to the drawing, a hood 15, made of a special textile fabric, is foldable as in Figure 1, and capable of assuming an inverted cup shape as in Figure 2, and is provided with a plurality of uniformly spaced tabs 16 along its circumferential edge.

Firmly connected to the tabs 16 are strong cords 17 of considerable length, their opposite ends converging into groups 18 attached at their terminals to a swing frame seat 19 suited to support a human body.

A sectional oval ring generally designated by the numeral 20, is formed by the arcuate tubes 21—22, each having crossbars 23—24 at their juxtaposed ends, one of the bars, as 23 provided with a pair of opposed spring clips 25 adapted to engage over the other bar, as best seen in Figures 3 and 4.

Plugs 26, fixed in the ends of one tube engage in the corresponding opening in the other tube, normally retain the ring intact but permit separation when under strain.

A plurality of rods 27, equal in number to the cords 17, have their inner ends rigidly secured in the ring 20 to extend radially and horizontally therefrom.

The outer ends of the rods are fixed in openings 29 in the reduced portions 30 of tubular guides 31, having smoothly beaded edges 32, and through which the cords 17 may freely pass, as at 33, as best seen in Figures 4 and 5, the cords thereafter being trained over the ring 20 on their way to the seat 19.

From the foregoing it will be seen that the several cords are held normally distended when ready to operate and that the holding means are merely thin rods, not affecting the entrance of air to the parachute at a critical moment, and this effect is further enhanced by separation of the frame ring 20 when the apparatus is weighted, as in supporting a person.

The parachute may be collapsed, as shown in Fig. 1, and suspended from a retaining means (not shown) on a wall, or, if desired, suitably folded and stored in any convenient manner for ready access when needed.

Although the foregoing is descriptive of the best known embodiment of the invention, it will be apparent that changes in proportions and construction may be made within the scope of the appended claims.

Having thus described the invention, what is claimed as new and sought to secure by Letters Patent, is:

1. In a parachute having a hood and a seat member, a rigid sectional frame ring, radial rods extending from said frame, said rods having tubular guides at their ends, and cords connecting said seat member and hood, said cords passing through said guides whereby they are held distended.

2. In a parachute having a hood and a seat member, a rigid sectional frame ring, radial rods extending from said frame, said rods having tubular guides at their ends, and cords connecting said seat member and hood, said cords passing through said guides whereby they are held distended, and over said frame ring to converge at said seat member.

3. In a parachute having a hood and a seat member, a rigid sectional frame ring, means normally retaining the sections of said ring in juxtaposition, radial rods extending from said frame, said rods having tubular guides at their ends, and cords connecting said seat member and hood, said cords passing through said guides whereby they are held distended, and over said frame ring to converge at said seat member.

GIUSEPPE TOMASETTA.
